UNITED STATES PATENT OFFICE.

THEODORE COMPTON, OF INDIANAPOLIS, INDIANA.

EXCAVATOR AND LOADER.

Application filed October 29, 1921. Serial No. 511,324.

To all whom it may concern:

Be it known that I, THEODORE COMPTON, a citizen of the United States, residing at Indianapolis, in the county of Marion and State of Indiana, have invented a new and useful Excavator and Loader, of which the following is a specification.

This invention relates to combined excavating and loading devices, the primary object of the invention being to provide means for moving a scoop to a position where the contents thereof may be readily and easily discharged to load the contents into a vehicle, of the usual construction.

Another object of the invention is to provide a carriage to receive the scoop and support the weight of the scoop and its contents while the same is being moved to a dumping position.

A further object of the invention is the provision of means to operate the carriage and scoop, whereby the same may be moved to the upper end of the device.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawings:

Figure 1 is a perspective view of a device constructed in accordance with the present invention, and illustrating the scoop and carrier in their dumping positions.

Figure 2 is a front elevational view of a scoop, the carrier being shown in section.

Figure 3 is an enlarged detail view disclosing the means used for connecting the scoop to the carrier.

Figure 4 is an enlarged detail view disclosing the rollers and their connection with the inclined track-way.

Referring to the drawings in detail, the device includes a support or body portion indicated generally by the reference character 5, which body portion is supported by means of the axle 6 and wheels 7 and 8.

The axle 6 is secured to the beam 9, which is shown as extending transversely of the body and provides the main support for the body, suitable bands 10 being provided to

secure the axle 6 to the beam 9. At the forward end of the device are the vertically disposed spaced angle irons 11 which are braced, and held in their proper spaced relation, by means of the angularly disposed bars 12, a bar 13 being provided to connect the angle irons 11 at their upper ends.

Supported by these angle irons 11 at a point substantially intermediate the ends thereof, is a loading hopper 14, which is formed with a discharge spout at the lower end thereof, the discharge spout being controlled by the hinged door 15, which may be opened and closed at the will of the operator to accomplishing the loading of a vehicle, which is moved to a position under the spout.

A laterally extending frame including the arms 16 and bar 17, is disposed adjacent to the upper end of the angle irons 11 and supports the pulleys 18 over which the operating cable 19 moves to accomplish the moving of the carrier and scoop to a dumping position. This cable 19 is shown as connected to the scoop 20 as by means of the chain sections 21, the cable passing from the innermost pulley 18, over the pulley 22, which is disposed adjacent to the body of the device, the cable passing to the drum 23 which is supported by the body as clearly shown by Figure 1 of the drawing.

Associated with the drum 23 is a drum 24 on which the cable 25 is wound, when the carrier and scoop are moved to their lowermost positions, and since the drums 23 and 24 are mounted on the same shaft and the cables 19 and 25 are oppositely wound on their respective drums, it is obvious that upon movement of one drum in one direction to wind its cable thereon, the cable on the opposite drum is unwound.

As shown, the cable 25 passes over the pulleys 26 from where the same passes to the carrier 27 and has connection therewith. This carrier 27 is formed preferably of sheet metal, and is of a width slightly greater than the width of the scoop 20 which moves therein. Vertically extending arms 28 are secured to the side walls of the carrier 27 and extend to points above the upper edges of the side walls, where the same are provided with notched portions 29 to accommodate the laterally extending arms 30 forming a part of the scoop proper.

The vertically disposed angle irons 11 are also braced by means of the inclined track-

ways 31 which are connected to the body adjacent to the lower ends thereof, the upper ends of the trackways extending inwardly and downwardly towards the hopper 14 so that the carrier will be directed downwardly to discharge the load of the scoop, directly into the hopper.

Pairs of rollers indicated at 32 are carried adjacent to the forward end of the scoop 10 and engage under the trackway, while the rollers 33 which are supported adjacent to the rear end of the scoop contact with the tread portion of the trackway. Thus it will be seen that the carrier is held to the track-way, and properly tilted when the same reaches the limit of its upward movement.

In order that the inclined trackway 31 will be held in its proper inclined position, bracing bars 34 are provided, which also extend forwardly and connect with the hopper 14 as shown at 35. The rails 36 which form the trackway 31 are held in proper spaced relation by means of the spacing bars 37.

It might be further stated that a suitable power device, such as an internal combustion engine indicated at 38, may be employed for operating the drums 23 and 24, to cause the operation of the device.

In the operation of the device, the scoop is 30 moved through the earth, by means of the cable 19, whereupon the same is directed to the carrier 27, which in its normal position, is held adjacent to the lower end of the trackway. The scoop now passes onto the carrier 35 where the laterally extending arms 30 contact with the members 29 to connect the scoop to the carrier.

It follows that upon further movement of the cable 19, which is now being wound on the drum 23, the scoop and carrier together with the contents of the scoop are moved to a position as indicated by Figure 1 of the drawings, where the same discharges its load into the hopper 14. As the hopper 14 45 becomes filled, the closure 15 may be oper-

ated to allow material to discharge from the hopper and into a suitable conveyor or vehicle.

Having thus described the invention, what is claimed as new is:—

1. In a combined excavator and loading machine, a wheel supported body portion, an inclined track having its upper end terminating at a point above the body portion, a hopper disposed adjacent to the upper end of the inclined track, a carrier having rollers and adapted to move over the track, said carrier having upwardly extending arms, a scoop adapted to move onto the carrier, laterally extending arms on the scoop and adapted to engage the upwardly extending arms of the carrier for connecting the scoop and carrier, means having connection with the scoop for moving the scoop and carrier over the track, and said arms of the scoop adapted to disengage the arms of the carrier when the scoop is moved to its loading position.

2. In a combined excavator and loading machine, a body portion, a frame supported by the body portion, a hopper supported by the frame, an inclined track supported by the body portion and having a right angled upper end portion overlying one end of the hopper, a carrier movable over the track section, a scoop adapted to move within the carrier, means secured to the carrier and contacting with the scoop for moving the carrier over the track with the scoop, means for moving the scoop to the right angled portion of the track where the same may dump its contents into the hopper, and means for returning the carrier to its normal position.

In testimony that I claim the foregoing as my own, I have hereto affixed my signature in the presence of two witnesses.

THEODORE COMPTON.
